UNITED STATES PATENT OFFICE.

KARL FREDRICK GUSTAV MAIER, OF SOUTH ASHBURNHAM, MASSACHUSETTS.

WOODWORKING-MACHINE.

1,276,550.

Specification of Letters Patent. Patented Aug. 20, 1918.

Application filed October 10, 1916, Serial No. 124,765. Renewed September 29, 1917. Serial No. 194,082.

To all whom it may concern:

Be it known that I, KARL FREDRICK GUSTAV MAIER, citizen of the United States, and resident of South Ashburnham, in the 5 county of Worcester and State of Massachusetts, have invented certain new and useful Improvements in Woodworking-Machines, of which the following is a specification.

10 This invention relates to wood working machines and in regard to certain more specific features thereof to pattern feed mechanism therefor.

The invention has for one of its objects to 15 provide a device of the character above referred to which will be simple in construction, inexpensive and durable.

Another object lies in a provision of a reliably efficient pattern and pattern feed which 20 is adapted to be operated by relatively unskilled workmen and upon machines employing high speed tools.

Other objects will be in part obvious and in part pointed out hereinafter.

25 The invention accordingly consists in the various features of construction, combinations of elements and arrangements of parts which will be exemplified by the construction hereinafter set forth and the scope of the 30 application of which will be indicated in the following claims.

Referring to the drawings wherein is illustrated one of various possible embodiments of the invention:

35 Figure 1 is a top plan view of a chair-seat shaping machine embodying the invention.

Fig. 2 is a side elevational view, partly in section, of the machine shown in Fig. 1.

In the drawings similar reference characters refer to similar parts throughout the 40 different views and there is indicated at 1 a base bearing the body or upright 2 which flares as indicated at 3 into a table or support for the work to be operated upon.

45 Upon opposite sides of the body 2 there are provided bearing brackets 4 which serve to support vertical cutter shafts 5, one on either side of the body. Each cutter shaft is provided with a pulley 6 driven by belting from 50 the main drive shaft (not shown in the drawings). Attention is called to the fact that one of the pulleys 6 is driven through a straight belt and the other through a cross belt to cause opposite rotation of the cutters 55 respectively. Secured to the top of the table 3 are brackets 7, one for each cutter shaft,

and the upper portion of the cutter shafts project loosely through the brackets respectively. A cutting tool 8 is fixed on each cutter shaft above the plane of the bracket 7. 60 Below the plane of each bracket 7 are idlers 8' each journaled in the table 3. It will be obvious, however, that these last said parts may be fixed to the table or integral with the brackets without departing from the scope 65 of the invention. The idlers are for a purpose which will hereinafter appear.

In line with each of the brackets 7 there are arranged, respectively, adjustable brackets 9. These brackets carry the journals 10 70 for a horizontal countershaft 11 having provided thereon a step pulley 12 driven through a belt 13 from the main driving shaft of the machine. Shaft 11 is formed with worms 14 and 15 having their driving 75 tendencies in opposite directions. These worms coöperate with worm wheels 16 and 17 to drive the stub shafts 18 and 19 in respectively opposite directions. Brackets 9 serve to provide bearings for these stub 80 shafts. Below the brackets 9 and secured to the stub shafts 18 and 19 are sprockets 20 and 21 respectively. The sprocket 20 drives an endless chain 22 the free loop of which is carried around one of the idlers 8' and the 85 sprocket 21 drives an endless chain 23 the free loop of which is carried around the other idler. It will be seen that the chains 22 and 23 are moved in reverse directions and at a relatively low speed due to the 90 worm and the worm wheel construction just described.

In practice it is desirable to employ cutting tools of high speed for shaping chair seats and similar articles. It is also found 95 desirable to keep the direction of cutting with the grain of the work. Formerly if the high speed cutter should catch in the work the liability of injury to the operator has been great. By the present invention 100 this liability is reduced to a minimum without in any way restricting the free manipulation of the work toward and from the cutting tool. To this end a pattern 24 is provided having engaging members 25 project- 105 ing laterally from the periphery of the pattern preferably in the form of teeth, as shown, which engage with successive links of the chains 22 and 23. When the pattern is coöperating with the chain 23 the feed 110 is in one direction and against the cutting direction of the coöperating tool. When the

pattern is engaged with the chain 22 its feed is in opposite direction and also against the cutting direction of the coöperating tool. The work 26 may be secured to the pattern 5 in any suitable manner. Where the chair seat is in the form of a frame clamps may be used such as indicated at 27. It will be obvious that some suitable clamping device might be employed if the chair seat was of 10 a solid character.

The pattern 24 is provided with a smooth pattern edge 28 which is adapted to be urged against a projecting portion or guide member 29 of either of the brackets 7. If 15 desired the pattern may be equipped with a handle as indicated at 30.

In the operation of the apparatus the cutters 8 are rotated at high speed in opposite directions. The chains or pattern feed 20 devices are driven at comparatively low speeds. The operator clamps the work upon the toothed pattern and moves the same to bring the teeth into engagement with the links of one chain. The chain will serve to 25 move the pattern and work slowly in a direction opposite to the cutting direction of the tool 8 and this condition is permitted to continue until such time as the cutting will be improperly against the grain of the work 30 whereupon the pattern is retracted from the chain 23 and placed in engagement with the chain 22 to complete the operation. The worm gear construction on the pattern feed mechanism serves to lock the chains against 35 movement in reverse directions and if the cutting tool catches in the work the lateral projections or teeth of the pattern prevent the latter from being violently projected in the direction of cutting.

40 As many changes could be made in the above construction and many apparently widely different embodiments of the invention might be made without departing from the scope thereof, it is intended that all matter contained in the foregoing description 45 or shown in the accompanying drawings shall be interpreted as illustrative and not in a limiting sense.

I claim:

50 1. In an apparatus of the character described, in combination, a pattern, a pattern feed, a cutter for work mounted on said pattern, the pattern and feed having interengaging elements whereby the former is fed 55 by the latter oppositely to the direction of cutting while permitting movement of the pattern at will toward and away from the pattern feed, and means for restricting the movement of the pattern in a reverse direction.

60 2. In an apparatus of the character described in combination, a table, a pair of cutters, means adapted to rotate said cutters in respectively opposite directions and 65 proximate said table, a feed device associ-

ated with each cutter for moving work slowly against the direction of cutting, and a pattern and work holding device, adapted to rest loosely on said table, so it may be moved at will from one to the other of said cutters, comprising means for temporarily engaging the said feed device opposite either cutter.

3. In an apparatus of the character described in combination, a table, a pair of cutters, means adapted to rotate said cutters in respectively opposite directions and proximate said table, a feed device associated with each cutter for moving work slowly against the direction of cutting, and a pattern and work holding device, adapted to rest loosely on said table, so it may be moved at will from one to the other of said cutters, comprising means for temporarily engaging the said feed device opposite either cutter.

4. In an apparatus of the character described, in combination, a table, a pair of rotatable cutters spaced apart and lying in a horizontal plane above said table, means adapted to rotate said cutters in respectively opposite directions, a feed device associated with each cutter for moving work slowly against the direction of cutting, a pair of abutments, and a pattern and work holding device adapted to be moved freely about on said table, said pattern comprising a pattern guide edge and a pattern feed edge, the former being adapted to coöperate with the said abutments and the latter with the said feed device, during the cutting operation.

5. In an apparatus of the character described in combination, a table, a pair of cutter shafts at right angles thereto, a cutter on each of said shafts, means for rotating said cutters in respectively opposite directions, a pattern feed coöperatively associated with each of said cutters, means adapted to actuate the pattern feed of each cutter in a direction to move the work against the direction of cutting, and a pattern and work holding device movable at will on said table and comprising a pattern feed edge which the operator may cause to engage temporarily with the pattern feed of either cutter as desired.

6. In an apparatus of the character described, in combination, a pattern, a pattern feed, a cutter for work mounted on said pattern, the pattern and feed having interengaging elements whereby the former is positively fed by the latter oppositely to the direction of cutting and throw-back by the cutter is prevented while permitting free movement of the pattern toward and away from the pattern feed.

7. A machine of the character described comprising, in combination, a pattern adapted to be connected to the work to be treated, a rotary tool for operating on the work, a

- guide member for the pattern, a feed element movable in an endless path, said pattern and feed element having interengaging portions for positively feeding the pattern 5 and article relatively to the tool, and means to rotate the latter, said tool, guide member and feed element being at the same side of the work and pattern to enable presentation of the pattern and work thereto when moved 10 in one direction and their removal from said parts when moved in an opposite direction.
8. A machine of the character described comprising, in combination, a pattern adapted for connection with an article, a rotary tool for operating on the article, a guide member for the pattern, and a feed element movable in an endless path, said pattern and feed element having interengaging parts for positively feeding the article relatively to 15 the tool, and said guide member and feed element being in superposed relation for enabling lateral presentation of a side of said pattern concurrently to said guiding means and feed element.
- 20 9. A machine of the character described, comprising in combination, a pattern for an article, a rotary tool for operating upon the article, a feed element movable in an endless path, interengaging parts for said pattern and feed element to feed the article positively relatively to the tool, a guide for the pattern and means to rotate the tool, said feed element, guide and tool being disposed in axial alignment permitting lateral 25 presentation of a side of the pattern and article concurrently thereto.
10. A machine of the character described, in combination, a movable pattern for an article, means adapted to secure the article 30 to the pattern for movement therewith, a rotary tool mounted to operate on a peripheral edge of the article, said pattern being laterally movable at the will of the operator to bring an edge of the work into and out 35 of engagement with said tool, and means to feed the article relatively to the tool including a rotor, a shaft, a worm gear thereon, and a worm to rotate said gear and prevent slip or reverse rotation of said rotor.
- 40 11. A machine of the character described
- comprising, in combination, a pair of rotary tools, means to rotate the same in opposite directions, pattern means for an article movable to present the article alternatively to said tools at will, and separate feeding devices associated with said cutters and coöperating with said pattern means to feed the article relatively to said cutters. 45
12. In a machine of the character described, in combination, a table, an upright shaft rotatable at high speed and carrying a tool, a low speed feeding element movable about said shaft, a pattern adapted to be moved on said table, and means whereby work may be secured to said pattern in position to be operated upon by said tool, said pattern and feeding element having interengaging portions providing for the positive transmission of movement to the pattern without clamping the pattern to the feed element. 50
13. In a machine of the character described, in combination, a table, an operating device above the table, comprising a slow feed element, a guide member and a high speed rotary tool positioned in different horizontal planes, a pattern and work holding device having means for interengaging said feed element, said pattern device being movable laterally against said operating device 55 to cause feeding engagement and simultaneous engagement of the work with said tool. 60
14. In a machine of the character described, in combination, a table, an operating device above the table comprising a slow feed element, a guide member and a high speed rotary tool positioned in different horizontal planes, a pattern and work holding device having means for interengaging said feed element, said pattern device being movable laterally against said operating device 65 to cause feeding engagement and simultaneous engagement of the work with said tool, and laterally away from said operating device to interrupt the feed. 70
